United States Patent Office

Des. 209,991
Patented Jan. 23, 1968

209,991

COPY CAMERA OR SIMILAR ARTICLE

**Murray Hoffman, 240 Jerusalem Ave.,
Hicksville, N.Y. 11801**

Filed Apr. 18, 1966, Ser. No. 1,919

Term of patent 14 years

(Cl. D61—1)

FIG. I

FIG. 1 is a top plan view of a copy camera or similar article, showing my new design;

FIG. 2 is a front elevational view;

FIG. 3 is a side elevational view;

FIG. 4 is a side elevational view opposite to that shown in FIG. 3; and

FIG. 5 is a rear elevational view.

I claim:

The ornamental design for a copy camera or similar article, substantially as shown.
